(57) **CLAIM**

The ornamental design for a label as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a label, showing my new design; and,

FIG. 2 is a rear view thereof.

The broken lines in the drawings define the bounds of the claimed design and form no part thereof.
